UNITED STATES PATENT OFFICE.

THEODORE P. BROWN, OF WORCESTER, MASSACHUSETTS, ASSIGNOR TO EARLE E. CONWAY, OF BOSTON, MASSACHUSETTS, CARLE C. CONWAY, OF NEW YORK, N. Y., AND THE SAID THEODORE P. BROWN, TRUSTEES, DOING BUSINESS AS SIMPLEX PLAYER ACTION COMPANY.

PNEUMATIC PLAYER ACTION FOR MUSICAL INSTRUMENTS.

Application filed November 7, 1921. Serial No. 513,620.

To all whom it may concern:

Be it known that I, THEODORE P. BROWN, a citizen of the United States, residing at Worcester, in the county of Worcester and

5 Commonwealth of Massachusetts, have invented a new and useful Improvement in a Pneumatic Player Action for Musical Instruments, of which the following, together with the accompanying drawings, is a specification.

10 My invention relates to pneumatic player actions for musical instruments and has for its object to provide an improved arrangement of the parts for actuating a player 15 action, whereby the operation of the instrument is greatly improved.

When operating pneumatic player pianos of the type heretofore constructed, it has been found that when the operator first 20 starts pumping to exhaust the usual bellows or air reservoir, the vacuum produced during the first few minutes of pumping is usually not great enough to simultaneously seat all of the valves controlling the pneumatics. Consequently, the valves often tend 25 to flutter, particularly if the operator fails to pump strongly, thereby resulting in objectionable noises prior to the playing of a music sheet by the instrument.

30 By my invention, I propose to substantially eliminate all possibility of the valves fluttering by providing improved means whereby the suction created by the pump is not applied to the valves until the air reservoir or bellows has been collapsed a sufficient amount to provide enough suction to 35 positively seat all of the valves at once, preparatory to playing a music sheet. My invention further contemplates improved 40 means whereby the valves controlling the pneumatics are entirely shut off from the pump when rereading a music sheet. The above, and other advantageous features of my invention will hereinafter more fully 45 appear, reference being had to the accompanying drawings, in which

Figure 1 is a view, partially in section and partially in side elevation, showing my invention applied to the pump and bellows 50 of a pneumatic player action, the pump and bellows being shown at right angles from their normal position to more clearly illustrate the relation of the parts.

Figure 2 is a transverse sectional view illustrating a portion of the pneumatic player 55 action of a musical instrument to which my invention is applied.

Figure 3 is an enlarged sectional view showing the details of one of my improved valves as employed in Fig. 2, together with 60 its associated pneumatic.

Like reference characters refer to like parts in the different figures.

Referring to Fig. 1, a vacuum pump 1 of the type usually employed in pneumatic 65 player actions, is mounted below the key bed 2 of the instrument, and is adapted to be operated by one or more suitable foot 70 pedals 3 which normally face toward the operator, but are here shown turned through substantially 90° to more clearly illustrate the application of my invention thereto.

The pump 1 is connected to a reservoir or bellows 4 so that the operation of the pump by the pedals 3 will cause air to be 75 exhausted from the bellows 4, in the usual manner. The bellows 4 is further connected to the pneumatic player action of the piano by means of pipes 5 and 6, and an air control box 7 is placed between the pipes 80 5 and 6 in order to control the passage of air to the bellows from the player action, as will be hereinafter described.

The control box 7 provides a chamber 8 within which is received one end of the 85 pipe 5. The pipe 6 also extends into the box 7 and is provided with a reduced portion 9 projecting into the chamber 8. The bottom of the box 7 is provided with a recess 10 located immediately below the open 90 end of the pipe portion 9, and a flexible diaphragm 11 separates the recess 10 from the chamber 8. A tube 12 leads into the recess 10 from a block 13 secured to the under side of the key bed 2. The block 13 is provided with a longitudinal passage 14 extending therethrough and connecting the tube 12 to a second tube 15 which leads to a second block 16, also secured to the under side 95 of the key bed 2.

The block 16 is provided with a port 17 which is adapted to be closed by a flap valve 18 normally held in its closed position by a spring 19. In the position of the parts shown in Fig. 1, however, the lower end of 105 the valve 18 is engaged by a portion of the

bellows 4 which are shown as being expanded. With the parts in the position shown, it is obvious that as soon as the operator moves the pedals 3 to work the pump 1, a suction will be produced in the chamber 8 through the pipe 5, and as the under side of the diaphragm 11 is maintained at atmospheric pressure through the tubes 12 and 15 and the open port 17, the diaphragm will 10 be drawn upwardly to close the open end of the pipe 6. This closes off the player action from the bellows 4 until the latter has been collapsed enough to allow the valve 18 to close the port 17 under the pressure of 15 the spring 19, and it is obvious that this does not occur until a considerable vacuum has been produced in the bellows. When the port 17 is thus closed by the valve 18, the diaphragm 11 falls away from the open end 20 of the pipe 6, owing to the existence of substantially atmospheric pressure in this pipe and the provision of a vent opening 20 between the recess 10 and the chamber 8. When this occurs, the pipe 6 connects the 25 bellows 4 directly to the player action, which will now be described.

Referring now to Fig. 2, the player action consists of the usual series of hammers 21 mounted upon the action rail 22, each hammer being adapted to be operated by a jack 23 and a wippen arm 24. Each arm 24 is connected by a thrust rod 25 to a rocker arm 26, upon one end of which the rod 25 rests. Each rocker arm 26 is pivotally supported at a point intermediate its ends and is connected to a pneumatic 27 by means of a link 28. A spring 29 acting on the arm 26 normally tends to hold the parts in the position shown, in which all of the hammers 40 21 rest against the hammer rail 30.

As best shown in Fig. 3, each pneumatic consists of an expandable bellows portion 31 mounted upon a block 32 containing a valve mechanism for controlling the pneumatic. 45 The block 32 is provided with a passage 33 extending from the bellows portion 31 to the lower side of the block. The block 32 is further provided with a passage 34 extending from one edge thereof and communicating 50 with the passage 33 through port 35. A valve 36 normally rests on a shoulder 37 surrounding a port 38 in the lower face of the block 32. A stem 39 of the valve 36 extends upwardly through the port 35 and 55 terminates just below a flexible diaphragm 40 that separates passage 34 from a recess 41 also provided in the block 32. The passage 34 of each block 32 is connected to an exhausting chamber 42 that is in turn connected to the pipe 6 leading from the air control box 7 and the bellows 4. The recess 41 in each block is connected through a passage 41^a to a tube 43 of a tracker bar 44 that is provided with a plurality of openings 45 for receiving all of the tubes 43 lead-

ing from the valve mechanism. The tracker bar 44 is adapted to support a music sheet 46 extending between a music roll 47 and a winding roll 48, the sheet 46 being provided with note perforations adapted to 70 register with the openings 45, as the sheet 46 is moved over the tracker bar 44 in the usual manner.

Referring again to Fig. 1, a lever 49 is pivotally mounted on the key bed 2 and, in the position shown, is adapted to so control the operating mechanism of the piano as to cause the music sheet 46 to be wound upon the roll 48 from the music roll 47. The lever 49 is provided with a link 50, to which is connected a valve 51 which, in the position shown, is adapted to cover a port 52 provided in the block 13 and communicating with the passage 14 extending through the block 13 between the tubes 12 and 15. The port 52 is adapted to remain covered as long as the lever 49 remains in the position shown for winding the music sheet on the roll 48. When, however, the lever 49 is moved to the left into the position shown in the dotted lines, to cause the music sheet 46 to be rewound upon the music roll 47 after a roll of music has been played, the valve 51 is moved to the right to uncover the port 52, for a purpose to be 90 95 hereinafter described.

Having thus described the various parts entering into my invention, the operation thereof is as follows:—The operator, having placed the music roll 47 in position, and having connected the music sheet 46 to the winding roll 48, moves the lever 49 to the position designated "Roll" and starts to move the pedals 3. The pump 1 thereupon tends to suck air from the player action through the then expanded bellows 4, but as the port 17 is then open, the diaphragm 11 immediately closes the open end of the pipe 6 and shuts off the player action from the bellows. At this moment all of the valves 36 are seated on the shoulders 37 so as to shut off the pneumatics 27 from the outside air, by closure of the lower ports 38. 110

As the operator continues to pedal, the pump 1 starts to exhaust the air from the bellows 4, thereby causing the latter slowly to collapse. When the bellows 4 collapse to a predetermined point, the valve 18, acting under the pressure of the spring 19, closes the port 17, whereupon the diaphragm 11 uncovers the end of the pipe 6 and establishes an uninterrupted connection between the player action and the bellows. When this occurs, it is obvious that the upper face of all of the valves 36 will 115 be subjected to the suction created by the bellows 4, while the under sides of the valves 36 will be subjected to atmospheric pressure, whereupon all the valves 36 will be raised simultaneously to close the ports 35 between 120 125 130

the valve passages 33 and 34. When this occurs, all of the bellows portions 31 of the pneumatics 27 will be fully distended.

In the meantime, the music sheet 46 will 5 have been wound upon the roll 48 sufficiently to cause one or more note openings in the sheet 46 to register with one or more openings 45 in the tracker bar 44. When a note opening registers with an opening 45, it is 10 obvious that air at atmospheric pressure will be admitted to the corresponding tube 43 and to the corresponding recess 41 in the valve block 32. The diaphragm 40 will thereupon move the corresponding valve 36 15 downwardly to close the port 38 and to connect the bellows portion 31 to the exhausting chamber 42 through the port 35. The suction of the bellows 4 will thereupon draw air from the pneumatic and cause the portion 31 to collapse and move the rocker arm 26 in a counterclockwise direction through 20 the link 28. This movement of the rocker arm 26 will be transmitted to the corresponding hammer 21 through the rod 25 and 25 jack 23 and will cause a note to be struck by the hammer. It is obvious that the above described sequence of movements will occur 30 each time that a note opening in the music sheet 46 registers with an opening 45 in the tracker bar 44.

From the foregoing, it is apparent that by my invention I have provided an improved arrangement whereby all of the valves for operating the pneumatics of the 35 player action are adapted to be simultaneously and positively seated in position to operate the pneumatics before the commencement of the playing of the music sheet, so that there is no possibility of the 40 valves fluttering, due to the fact that not enough suction has been created by the bellows 4. In other words, my invention automatically renders the bellows noneffective for seating the valves until after enough 45 suction has been created to simultaneously bring all of the valves to their operating position. Furthermore, my invention provides means whereby the player action is automatically cut off from the bellows when 50 it is desired to reroll a music sheet after it has been played. This is believed to be a distinct improvement over prior constructions in which the suction created by the necessary operation of the pump when re- 55 rolling is very liable to cause fluttering of the valves. With my improved construction however, the opening of the port 52 permits the pump 1 to draw the air directly through the tube 12 rather than from the 60 player action, as in previous constructions.

While I have shown my invention as applied to a particular arrangement of parts of a player action, it is not so limited but is susceptible of various modifications within 65 the scope of the appended claims.

I claim,

1. In a player for musical instruments, the combination with a valve mechanism for controlling a pneumatic player action and a suction creating device, of means controlled 70 by said suction device for preventing the connection of said valve mechanism to said device until after the creation of a predetermined amount of suction by said device.

2. In a player for musical instruments, 75 the combination with a valve mechanism for controlling a pneumatic player action and a suction creating device, of means for automatically connecting said valve mechanism to said device when a predetermined amount 80 of suction has been created thereby.

3. In a player action for musical instruments, the combination with a valve mechanism, a collapsible air reservoir and means for exhausting said reservoir, of means controlled from said air reservoir for preventing the connection of said reservoir to said valve mechanism until after the latter has 85 been collapsed a predetermined amount.

4. In a player action for musical instruments, the combination with a valve mechanism, a collapsible air reservoir and means for exhausting said reservoir, of means for automatically connecting said valve mechanism to said reservoir when the latter has 90 been exhausted a predetermined amount.

5. In a player action for musical instruments, the combination with a valve mechanism, a collapsible air reservoir and means for exhausting said reservoir, of means controlled by the degree of exhaustion of said reservoir for connecting said valve mechanism to said reservoir. 100

6. In a player action for musical instruments, the combination with a valve mechanism, a collapsible air reservoir and means for exhausting said reservoir, of means controlled by the amount of air in said reservoir for connecting said valve mechanism to said reservoir. 105

7. In a player for musical instruments, the combination with a plurality of valves each adapted to control a pneumatic, and a suction creating device, of means controlled 115 by said suction device for preventing the connection of said valves to said device until after the latter has created enough suction to simultaneously operate all of said valves.

8. In a player for musical instruments, the combination with a plurality of valves each adapted to control a pneumatic, and a suction creating device, of means for automatically connecting said valves to said device after the latter has created enough suction to simultaneously operate all of said 120 valves.

9. In a player mechanism for musical instruments, the combination with a suction creating device, a plurality of pneumatics, and a plurality of valves each adapted in one 130

position to shut off its pneumatic from said device, of means for automatically connecting said valves to said device after the latter has created enough suction to simultaneously move all of said valves in position to cut off said pneumatics from said device.

10. In a player mechanism for musical instruments, the combination with a collapsible air reservoir, means for exhausting the reservoir, a plurality of pneumatics and a plurality of valves each adapted to be seated by gravity to connect its pneumatic to said reservoir, of means for automatically connecting said valves to said reservoir only 15 after the latter has been exhausted enough to simultaneously raise all of said valves to shut off said pneumatics from said reservoir.

11. In a player mechanism for musical instruments, the combination with a suction creating means, a vacuum chamber for op-

erating actuating pneumatics and a member for controlling the direction of movement of a music sheet, of a valve mechanism adapted to shut off said suction creating means from said vacuum chamber until such time as a predetermined suction is obtained, and additional means for closing said valve by the operation of said member.

12. In a player mechanism for musical instruments, the combination with a suction creating means, a vacuum chamber for operating actuating pneumatics and a member for controlling the direction of movement of a music sheet, of a diaphragm adapted to close the connection between said vacuum chamber and said suction creating means prior to the establishing of a predetermined degree of vacuum, said diaphragm being also controlled by said member.

THEODORE P. BROWN.
